UNITED STATES PATENT OFFICE.

RICHARD SCHNEIDER, OF FLUSHING, NEW YORK.

SHUTTER.

Application filed October 25, 1920. Serial No. 419,198.

To all whom it may concern:

Be it known that I, RICHARD SCHNEIDER, a citizen of the United States, residing at Flushing in the county of Queens and State 5 of New York, have invented certain new and useful Improvements in Shutters, of which the following is a specification.

The main object of this invention is the provision of a shutter of simple construction, which may be readily attached and installed and easily manipulated.

The above and other objects will become apparent in the description below, in which like characters of reference refer to like 15 named parts in the drawings.

Referring briefly to the drawings,

Figure 1 is a front elevational view of the shutter structure casing assembled.

Figure 2 is a partial side elevational view, 20 partial sectional view of the same.

Figure 3 is a perspective view of one of the shutter elements in detail.

Figure 4 is a plan view of the shutter when the elements are in an open position.

Figure 5 is a transverse sectional view 25 taken substantially through the center of the same.

Figure 6 is a view similar to Figure 4 but showing the parts in a closed position.

Although the original purpose of this invention was for controlling heat it has been found useful for many like purposes and therefore may be used with or without the outer casing in which it is shown.

This casing is comprised preferably of a 35 thin walled metallic box 12, an oblong rectangle in shape, supported by hangers 17 at the upper rear corners and provided with an inlet 11 adapted to be connected with any convenient supply of heat.

Extending centrally outward from the front wall is a hollow frusto-conical member 13, its base being outermost, the same communicating with the interior of the casing 40 through the opening 14.

Fixed to the inner sides of the front wall is a flanged band 24 formed with a cover plate 25 spaced parallel with the front wall and having a central circular opening 26.

Seated against the inner side of the plate 50 25 is a disc 27 having an opening 28 registering with the opening 26 and on the disc is a ring 18 projecting towards the front wall of the casing 12, this ring having an annular

groove 21 in its periphery into which extend the raised elements of the brackets 22,

of Z shaped cross section secured to the front wall of the casing within the band 24, these brackets centering and supporting the ring and disc in an obvious manner. 60

The interior of the ring is provided with gear teeth and is in effect an internal gear capable of being rotated by a handle 15 operatively extending through an elongated, arcuate slot 16 in the front wall of the casing 65 as best shown in Figure 1.

Set in a circular row in the casing 12, at uniformly spaced intervals are pins 19 upon which are pivoted shutter elements 20, these shutters having a straight edge on one side 70 and an arcuately curved opposite or outer edge as shown in Figure 3.

These shutters are flat and smooth on both sides except at their pivoted end, which is increased in thickness as at 23 and provided with peripheral teeth engageable in the teeth of the ring 18 in such manner that upon operating the handle 15, the shutters may be simultaneously opened as shown in Figure 4 or closed as in Figure 6, with respect to the opening 28, indicated by broken lines thus providing either a clear passage therethrough or completely closing it. 80

Having thus described my invention, what I claim as new and desire to secure by Letters Patent, is:—

In a heat controlling shutter, the combination with a plate having an orifice, a frusto-conical member integral with said plate leading outwardly from the mentioned orifice, a 90 circular casing having a corresponding orifice in its rear wall secured to said plate, an internal gear rotatably mounted in said casing, an annular flange formed with said gear, said flange having an opening disposed in register with the mentioned orifices, a single means for manually rotating said gear, said means extending outward through said plate, a plurality of flat level shutters pivoted in spaced relation to said plate, said 95 shutters when open presenting a clear unobstructed passage through said plate, casing and gear flange the full area thereof and when closed preventing the passage of air therethrough, and toothed sectors on the outer thickened ends of said shutters, said 100 sectors operatively meshing with the tooth of said internal gear and being pivoted in said plate to operate within said casing.

In witness whereof I affix my signature.

RICHARD SCHNEIDER.
